REMOTE CONTROL

Samuel Herbert Lanyon, Oakland, Calif.

Application January 14, 1935, Serial No. 1,747

3 Claims. (Cl. 172—239)

My invention relates to a means for the remote control of devices requiring a movement which can be resolved into a rotational movement and more particularly to a remote control device which is exceptionally accurate and practically deadbeat.

Among the objects of my invention are: To provide a remote control device operable at a distance; to provide a remote control device which is accurate in its operation and which, regardless of its motion away from predetermined points, will reset to those points through the shortest arc and without substantial deviation; to provide a remote control device which is deadbeat in its action and which will not overrun due to inertia; to provide a remote control device which will not hunt; and to provide a remote control device adaptable for use in controlling radio equipment, elevators, shipboard rudders or in fact, any machine or instruments wherein the exact positioning of a part is to be controlled electrically.

Other objects of my invention will be apparent or will be specifically pointed out in the description forming a part of this specification, but I do not limit myself to the embodiment of the invention herein described, as various forms may be adopted within the scope of the claims.

Referring to the drawings, Figure 1 is the top view in elevation of a simplified remote control device adapted for about 180° total rotation and provided with only two cams in order to simplify the explanation of its operation.

Figure 2 is the wiring diagram reduced to lowest terms and simplified for clarity, no attempt being made to show the relative positions of cam-operated contacts.

Figure 3 is a cross sectional view of cam followers and cam contacts and associated mechanical lock, the cam itself being shown in elevation.

Figure 4 is a side view in elevation of the device of Figure 1, some of the parts being omitted.

Figure 5 is an elevational view taken at right angles to that shown in Figure 4, to show the relation of the gear shifting magnet to the remainder of the apparatus.

It is believed that the broad aspects of my invention can be more fully understood by direct reference to the drawings.

A shaft 1, rigidly connected to the shaft to be rotated, either directly thereby obtaining about 180° rotation or less, or through step-up gears thereby obtaining 360° rotation or several revolutions as desired, is mounted in a frame 2 on bearing apertures 4—4 passing through two opposite sides of the frame 2. Mounted on the shaft

between the two bearings are a plurality of cams 5. In Figure 1 only two are shown, but as many may be used as there are position settings of the shaft desired. As will later be seen, the position setting of the device is such that error is much less than one degree, so that if desired, 180 or more cams may be used. It will also be seen that a single cam may be used whereon a plurality of operating surfaces may be cut. I prefer, however, to describe the device as having separate cams, each of them being adjustable on the shaft as to rotation with respect thereto and being fixed in position by set screws 6. Outside of the frame is positioned a main driving gear 7 fixed on the shaft by a gear set screw 9.

An auxiliary frame 10 is fastened to the frame 2 by an angle arm 11 and the frame 10 carries mounted thereon a motor 12 having directional windings 13 and 14. Winding 13 is adapted to cause the motor to run in one direction when energized and winding 14 is adapted to rotate the motor in the opposite direction when energized. I do not desire, however, to be limited in any way by this type of motor as any reversing motor is perfectly satisfactory, particularly when supplied with three leads, a common lead and two other leads, one of which when energized with the common lead will cause the motor to run in one direction, the other when energized with the common lead, causing the motor to run in the opposite direction.

The motor shaft 15 is extended and carries upon it a brake drum 16 and a worm 17. Mounted also on the auxiliary frame 10 is a gear shaft 19 sliding through bearings in both frames, the gear shaft being parallel to the main rotatable shaft 1. The gear shaft 19 carries a pinion 20 which is adapted to be engaged with the teeth of the main gear 1 but which is held out of engagement from that gear by means of a spring 21, the distance that the pinion is removed from the main gear being determined by an adjustable stop 22. A driven gear 24 is positioned on the end of the gear shaft 19 in engagement with the worm 17, and is preferably made wide enough so that as the shaft 19 is shifted so that pinion 20 is engaged or disengaged from the main gear 1, the worm 17 and driven gear 24 are continually engaged. Thus, pinion 20 is rotating as it approaches the main gear 1, greatly aiding a quick and accurate engagement therewith.

I may desire, however, to prevent unchecked overrunning of the motor and I have, therefore, provided the gear shaft with a brake-actuating disc 25 which through a brake link 26 operates

a spring brake 21, normally in contact with drum 16 so that when the gears are out of engagement this brake will stop the rotation of the motor shaft quickly.

5 The end of the gear shaft 19 is preferably provided with a bevel 28 which engages with a shift lever 30, only the top of which is shown in Figure 1, the remainder of the shifting mechanism being shown in Figures 4 and 5, to which 10 I now refer.

Shift lever 30 is preferably resilient and is attached to an armature 31 of a magnet 32 by an angle bar 34, the armature being pivoted to a magnet core 35. Thus, when current is passed 15 through the magnet winding the armature is drawn up and the shift lever pressed against the gear shaft 19 forcing gear 20 into mesh with gear 7, the direction being as indicated by the arrow 36 in Figure 1. When current ceases to pass 20 through the magnet winding 32, spring 21 returns the gear shaft, thus immediately releasing shaft 1 from any connection with the motor. It will be noticed that during this shift, the 25 brake-actuating disc 25 pushes brake 21 away from the brake drum 16, thus allowing the motor to revolve freely and when the gear shaft 19 returns, the brake is applied. The electrical connection of the gear shift magnet to the motor 30 will be given later.

30 In case the complete remote control device is used, for example, on a radio set, it may be desirable that the radio set be muted during rotational movement and I have found it convenient to utilize a pair of contacts 31, one of 35 which is in contact with the brake-actuating disc 25, the circuit being closed by the motion of the gear shaft during engagement. There may be other desirable uses for this contact.

Referring directly to the cam contour and cam 40 contacts as shown in detail in Figure 3, I prefer to provide the cam with a semicylindrical operating surface 40 having a greater radius than the remaining portions 41. I also prefer to have the portion of greater radius or, as may be 45 more conveniently called, the high portion, occupy not more than 180° of the periphery of the cam, and I prefer to have a slanting transition area 42 on each end. The reason for this will be shown later.

50 On each cam, substantially opposite each other, I provide a pair of cam followers 44 and associated electrical contacts operated thereby. A description of one follower will serve for all. A cam follower 44 extends preferably radially 55 toward the periphery of the cam and passes through a cam follower body 46 mounted on a pivot 45. These cam followers are pinned in place by means of taper pins 47. The cam follower body 46 together with its cam follower is urged toward the periphery of the cam by a cam follower spring 48, and the distance through which the follower may travel toward the axis of the cam when not in contact with the high portion of the cam is controlled by means of a 60 cam follower limit screw assembly 50.

The cam follower is allowed, by adjusting screw assembly 50, to follow down the transition surface 42 a very slight amount, as the cam is 70 rotated, just sufficiently so that a slight rocking action is given to the cam follower body when the cam follower engages the transition surface and progresses onto the high portion of the cam during rotation of the cam. I then utilize this 75 rocking motion by attaching to the cam follower

body a contact arm 51 carrying a moving contact 52. I then position on the main frame a stationary contact 53 carried by a contact adjusting screw 54 so that the extent of the gap therebetween may be controlled. It will be noticed that by having the cam follower between the cam pivot and the contact carried by the cam follower body that I obtain a multiplication of the distance through which the contact 52 travels, over the actual distance of offset created 10 by the contact of the cam transition surface with the cam follower. I then adjust contact 53 so that the gaps are open when the cam follower is opposite the low portion 41 of the cam, but are closed when the cam follower is in contact 15 with the high portion 40 of the cam.

I utilize a cam follower adjustment screw 55 to adjust exactly the position of the cam followers themselves with respect to the transition points on the periphery of the cam so that when the cam is turned to bring both of the cam followers in contact with the opposite transition surfaces, and with the cam in that one position only, both gaps will be open. At all other positions within the operative arc of rotation one 20 or the other of the opposite gaps will be closed according to whether or not the associated follower is on the high portion of the cam.

On each cam I provide at one side of the high portion of the cam a lock brake 56 having a 30 notch 57 therein and then provide a fixed positioning wedge 59 urged into the notch by means of a lock spring 60. This mechanical locking arrangement is in reality a self-centering brake causing the cam to stop instantly, as will be later 35 explained, when both of the cam follower contacts are open, thus preventing riding by or hunting. In many cases, however, I find that such a lock is not necessary as frictional components of the mechanism which is actuated by 40 the shaft 1 are many times sufficient to prevent such riding by. It is to be understood that the lock may be placed at other locations around the cam periphery if desired.

The above description is concerned solely with 45 the mechanical structure of the device. The electrical hookup will next be explained, together with the way in which the device functions when so hooked up. Direct reference must, therefore, be had to a simplified wiring diagram, shown 50 in Figure 2, in which the mechanical structure has also been reduced to lowest terms. The six cams 5 indicated as positioned on shaft 1 are preferably adjusted so that lines drawn to the axis of the shaft from the beginning of the 55 high portion of the cams will be in the same different angular relationship as the six points at which it is desired that the rotation shall stop.

The opposite movable contacts 52, associated 60 with each cam, are connected together and each connection is brought out to individual selector contacts 61. These may conveniently be one contact of a series of interlocking switches 62, each of which will remain closed until released by operation of another or a release button, not shown. A source of electrical current will then be included between the other contacts of these switches such as a main power supply 63. One connection from mains 63 passes through the magnet winding 32 and thereafter is divided to 70 pass through motor windings 13 and 14. The emerging lead from winding 13 goes directly to all the stationary contacts 53 on one side of the cams and the emerging lead from winding 75

14 goes to all the stationary contacts 53 on the opposite sides of the cams.

In Figure 2 a conventionalized gear box 64 includes the magnet winding 32 and the gear shift. In this way, whenever any one of the selector contacts 61 is connected through the mains 63, the magnet winding 32 is energized, the motor energized and thrown in gear with the main shaft 1 carrying the cams, provided either of its related cam circuits is closed, thereby to rotate the main shaft 1.

The direction of rotation will be determined by the relative position of the cam contacts 52. Referring to any one cam, if the cam follower 15 on one side is in contact with the high portion of the cam, the gap between contacts 52 and 53 on that side will be closed, thus causing the motor to run in one direction, if the cam follower on the opposite side is on the high side of the 20 cam, the gap on that side of the motor will be closed and the motor will run in the opposite direction, depending on whether coil 18 or 14 is energized. It will be seen that both gaps cannot be closed simultaneously. Therefore, no 25 matter which of the opposite gaps is closed on the cam related to contacts 52 which are energized by the use of the respective switch, the motor will start in a direction determined by the closure of the gap and the motor will continue to run until both of these gaps are opened and the circuits connected thereto broken. As 30 this can only occur when the cam followers are one at the beginning and other at the end of the high portion of the cam, it may be seen that 35 the shaft will be rotated in either direction to stop at an angular position as determined by the cam setting. Inasmuch as when one cam is controlling the rotation of the shaft and the shaft is being rotated, all the other cams are also being 40 rotated, opening and closing the various opposing gaps as they rotate, so that when the shaft is again at rest after both contacts on a particular cam have been opened to stop the motor, when previously used switch 61 is opened and any other 45 switch closed to connect a circuit to other related cam contacts, the shaft will again be rotated by the motor and in the proper direction to travel through the shortest arc and give the setting to the shaft as determined by the setting 50 of that particular cam on the shaft. The first cam is thus reset again in condition to be moved back when current passes through the one closed contact. In case a switch is actuated in a circuit in which both gaps are already open, no 55 rotation occurs.

In this way, I have provided for settings within an approximate total of 180° rotation, always in the proper direction and amount. It is never necessary to go to the end of the rotational path 60 and return, as in the case with most remote control devices. As the breaking of the motor current by the opening of opposite gaps always causes current to be withdrawn from the gear shifting magnet, the motor is instantly taken out of gear and, as explained above, unless there is sufficient inertia to overcome frictional components on the shaft to be rotated, no overrunning will occur. It is obvious, however, that should overrunning occur, the other related contact will 65 be immediately closed and cause the motor to return the cam immediately towards its proper position. I have found, however, that such hunting does not take place when sufficient spring tension is placed on the gear shaft 18 by spring 70 21 to remove the motor influence from the shaft

1 quickly. The brake 27 is not provided to prevent overrunning of shaft 21, because overrunning of the motor would not cause such overrunning because of disengagement of the gears. It is only placed there to prevent unchecked overrunning of the motor and subsequent delay in proper action when two different switches 61 are closed in quick succession, to rapidly reverse the motor.

In order to prevent a trailing cam-follower from overtravelling the high portion of cam and causing accidental damage to the controlled apparatus at the ends of the desired total rotation of the main shaft should the motor continue to run, I prefer to provide limit switches 64 positioned to be operated by means of a pin 65 attached to the shaft 1. The pin is so adjusted with relation to the opposing switches so that when the end of the desired travel in one direction is reached, one limit switch will be opened and the motor stopped. When the shaft is then rotated through its complete angular range it will contact the other limit switch and open the other motor circuit. Thus, the main shaft can never be rotated by the motor through an angle more than required and no damage or tie-up can occur even if contacts 52 to 53 in use should fail to break.

I have found the arrangement as described to be extremely accurate in its stopping points. I have also found that by the use of the mechanical lock as described, I can obtain absolute accuracy, or at least that angular accuracy which can be obtained by the registry of the wedge 59 in the lock notch 67. The accuracy is well within one degree and I may therefore use more than 180 cams to obtain more than 180 different settings. It may be, however, more desirable to use one solid cam extending lengthwise past several pair of cam followers and mill out the low portions in the relative order and spacing desired, in which case, of course, no individual cam setting is possible. There are many cases, however, such as in the steering of a ship, or similar operation where for instance a one degree change with progressive or selective increments will take care of the entire operation. If, however, only six, eight, or ten cams are used to give a setup such as that, desirable for the operation of a radio receiver, and where the angular tuning location of stations desired will not be the same in one portion of the country as they are in the other, it is quite desirable that each cam be individually adjustable.

Adjustment is simple. All that is necessary is to loosen set screw 6 which locks the cam on the shaft, turn the shaft connected to the tuning condenser of a radio receiver to a good adjustment for the station it is desired to receive, then turn the cam until opposite related contacts 52-53 are open. The cam is then again locked onto the shaft by means of the proper set screw 6 and thereafter when the circuits attached to the opposing contacts 52-53 are completed the motor will always turn the shaft back to that point and stop. The same adjustment can be performed with all of the cams until they are positioned to turn the shaft to each of the settings desired. The switches 61 may then be labeled to conform to the cam setting as made.

It should of course be understood that the switches 61 are simply representative of any desirable form of contactors interlocked to open when another is closed. For example, these switches may be contacts on a thermometer or

thermostatic device whereby the contacts are closed at varying temperatures, utilizing the closure for the regulation of draft or feed of a burner for providing heat for houses, green houses or other places where a uniform heat is desired.

Again, I may desire to use my instant invention in conjunction with the automatic time control described and claimed in my application, Serial No. 705,670, filed January 8, 1934. This device comprises a traveling tape having holes punched therein allowing various contacts to be made at varying or equal time intervals with particular adaptation to the use of the device as an automatic preselective and manual remote control 15 for a radio set.

The device either as shown or so adjusted as to create a motion having uniform increments is also adapted for use as a repeater. A number of such devices may be operated in parallel by a 20 single set of contactors and the remote control devices themselves located in different geographical positions. Each one will then move to identical settings of angular rotation in response to the impulses sent out by the single controlling 25 set of contactors. An example of this type of use is a gyrocompass provided with repeating contacts, the remote control devices as herein described being positioned in various locations on a ship and faithfully reproducing the indications given by the main compass. A 2-1 step-up 30 would then be used to obtain 360° readings.

It is also within the scope of my invention to mount pivots 45 of the cam follower bodies 46 on a frame rotatable around the axis of a single 35 cam. With both gaps between contacts 52 and 53 open as shown in Figure 3, any rotation of the frame carrying the cam follower bodies will cause one of the related gaps to close, thus energizing the motor. The cam will then turn and 40 come to rest in a new position as determined by the new position of the cam followers. An electrical follow-up system of this sort has many applications in industry, as will be readily apparent to those skilled in the art.

While it is obvious in my preferred form that an operating arc of substantially 180°, as indicated by the high portion 48 in Figure 3, is the 45 arc within which the maximum number of position settings of other cams is possible, it is also to be understood that the relative position of the operating surface related cam followers should be such that at no time should the associated contacts be both closed, or both opened except when at the desired position, as determined by 50 the related cam. If these conditions are fulfilled, the high portion 48 may be greater or less than 180°, but the effective operative arc of the related cam cannot be greater than 180° although it may be less.

I claim:

1. In a remote control device, the combination with a shaft whose rotation is to be controlled and a motor for rotating said shaft, of a cam rotated by said shaft, a contact actuated by said cam to open during slightly more than one half of its arc of operation, a second contact similarly actuated to be open during slightly more than the other half of its arc of operation, whereby there is a single position whereat both of said contacts 10 are open, a circuit including said contacts and said motor and operative to rotate the motor in one direction when one contact is closed and in the other direction when the other contact is closed, a geared connection between said motor 15 and said shaft including a gear slidable to break said connection, electro-magnetic means in series with said circuit for sliding said gear into mesh when either of said contacts is closed, resilient means acting in opposition to said electro-magnetic 20 means to slide said gear out of mesh when both of said contacts are open, means for instantaneously arresting the motion of said cam at the open position of both contacts, and means operative on the disengagement of said geared 25 connection for braking said motor.

2. In a remote control device, the combination with a controlled shaft, a motor for driving said shaft, and a cam operated switching system for causing said motor to rotate in a direction adapted to drive said shaft through the shortest arc to a position predetermined by the setting of said cam, of a gear connection between said motor and shaft including a gear slidable to disconnect 30 said motor and shaft, electro-magnetic means in series with said motor and switching system for sliding said gear into mesh to drive said shaft when said motor is in operation, resilient means for sliding said gear out of mesh, and means operative upon the disengagement of said gear for 35 braking said motor.

3. In a remote control device, the combination with a controlled shaft, a motor for driving said shaft, and a cam operated switching system for causing said motor to rotate in a direction adapted 45 to drive said shaft through the shortest arc to a position predetermined by the setting of said cam, of a gear connection between said motor and shaft including a gear slidable to disconnect said motor and shaft, electro-magnetic means in series with said motor and switching system for sliding said gear into mesh to drive said shaft when said motor is in operation, resilient means for sliding said gear out of mesh, and means operative at the position of deenergization of said motor for stopping separately the motion of both 50 motor and shaft.

SAMUEL HERBERT LANYON.
